UNITED STATES PATENT OFFICE.

THURE LARSSON, OF WORCESTER, MASSACHUSETTS, ASSIGNOR TO HIMSELF, W. E. D. STOKES, OF NEW YORK, N. Y., AND FRED A. JONES, OF WORCESTER, MASSACHUSETTS.

DRILLING-MACHINE.

No. 877,572.

Specification of Letters Patent.

Patented Jan. 28, 1908.

Application filed May 22, 1903, Serial No. 158,316. Renewed June 20, 1907. Serial No. 879,926.

To all whom it may concern:

Be it known that I, THURE LARSSON, a subject of the King of Sweden, residing at Worcester, in the county of Worcester and 5 State of Massachusetts, have invented a new and useful Drilling-Machine, of which the following is a specification.

This invention relates to that class of drilling machines which are employed for 10 boring oil-wells, Artesian-wells, wells for long-run plunger elevators, or for similar purposes.

The especial objects of this invention are to construct the rotary head which transmits power for operating a drive-pipe so that it 15 may be used to assist in coupling on additional lengths of drive-pipe, and to provide self-oiling means for supporting and lubricating the rotary-head so that the same will act to automatically circulate the oil required for lubricating the bearings thereof.

To these ends, this invention consists of the drilling apparatus and of the combinations of parts therein as hereinafter described and more particularly pointed out in 20 the claims at the end of this specification.

In the accompanying three sheets of drawings, Figure 1 is a plan view of a drilling apparatus constructed according to this invention. Fig. 2 is a longitudinal sectional view 25 thereof. Fig. 3 is a detail view showing the guide-plates of the driving-head raised. Fig. 4 is a similar view showing the operation of the parts in coupling on an additional length of drive-pipe. Fig. 5 is a perspective view of 30 the lower end of the keyed or top section of drive-pipe, Fig. 6 is a perspective view of a plain section of drive-pipe and its coupling; and, Fig. 7 is a perspective view of one of the 35 cover plates.

40 In that class of machinery to which this invention relates, the boring or sinking of a hole into the ground is accomplished by a drill-cylinder which is turned by a drive-pipe. As the well is sunk, additional lengths of 45 drive-pipe are coupled on until the well reaches the desired depth.

This invention relates especially to the rotary-head which is employed for turning or rotating the drive-pipe.

50 In a drilling apparatus constructed according to this invention, the body portion of the rotary-head is provided with an annular groove, and is mounted to run on supporting rollers. The gearing for turning the

head is preferably arranged to automatically 55 convey oil for keeping the bearings lubricated. To accomplish this, the driving pinion runs in an oil-chamber or pocket so as to carry oil up to the gear-teeth on the underside of the cover, the oil which drops off of 60 these gear-teeth running down on to the bearing-rolls and thence back to the oil pocket which coöperates with the driving pinion. The connection between the rotary-head and the drive-pipe is made by movable 65 cover sections which are preferably hinged in place so that they may be turned back out of the way when the drive-pipe is to be lifted or raised out of the well. The cover sections also preferably coöperate to form a 70 wrench socket or recess which may receive the lower section of a driving-pipe-coupling, so that the rotary head may be used to assist in unscrewing or disconnecting sections of drive-pipe when it is desired to couple in a 75 new section of pipe.

Referring to the accompanying drawings for a detail description of an apparatus embodying this invention, as shown in Fig. 1, the construction comprises a wooden 80 frame-work consisting of side pieces 10 connected by cross-pieces 11. Bolted on to and supported from two of the cross-pieces 11 is a bearing or support 12, extending from which is a plate 13. Secured on the plate 85 13 of the bearing-piece 12 and on one of the cross-pieces 11 respectively, are bearing-boxes 14 and 15, journaled in which is a driving shaft 16 which may be turned from any suitable source of power, as for example, 90 from a belt-pulley, as shown.

The rotary head of a drilling apparatus constructed according to this invention, as herein illustrated, comprises a ring or body portion 17, and a cover or top 18. The 95 body portion 17 is provided with an annular groove and is mounted to run on supporting rollers 19 which are journaled on uprights or studs. Six supporting rollers 19 are preferably employed, as indicated by dotted lines 100 in Fig. 1.

Formed in the bottom of the bearing-piece 12 is an annular oil-channel having a pocket or deeper section 20. Dipping into the oil pocket 20 is a pinion 21 secured upon the 105 driving-shaft 16. The pinion 21 meshes with gear-teeth formed on the underside of the annular cover 18. I regard this as a

particularly advantageous way of mounting and operating the rotary head of a drilling machine, because by means of this construction the head will be journaled to turn with comparatively little friction, and the gearing will serve to automatically circulate the lubricating oil. That is to say, the pinion 21 will carry oil from the oil-pocket 20 up into the gear-teeth on the underside of the cover 18, from which the oil will drop down on to the bearing-rolls, as indicated, and then run back around the annular oil-channel to the pocket or oil-chamber 20.

The connection between the driving-head and the drive-pipe in an apparatus constructed according to my invention is most clearly illustrated in the third sheet of drawings. As shown therein, the drive-pipe may consist of one or more sections P which are coupled together by ordinary drive-pipe couplings A and B.

The upper or operative section of pipe C is provided on its opposite sides with keys or splines K, which, as shown most clearly in Figs. 1 and 2, serve to connect the top pipe section with the rotary head when the parts are in normal position, so that the drive-pipe will be turned or rotated, while at the same time, the key-and-slot connection will permit the drive-pipe to descend as the well is bored. The lowermost section of drive-pipe, as shown in Fig. 2, may have the drilling-cylinder D connected to its lower end. Hinged on to the part 18 of the rotary head are cover-plates 22 and 23. The cover-plates 22 and 23 may be locked in their closed position by tap-bolts 24 as shown in Fig. 1, and when in this position, the cover-plates 22 and 23 form the connection between the rotary head and the drive-pipe.

When the drive-pipe is to be raised for the purpose of adding another section of pipe, or for any other purpose, the hinged sections 22 and 23 may be opened as illustrated in Fig. 3, and in uncoupling the drive-pipe the sections 22 and 23 may be closed, and the lower part of the coupling A may be seated in the wrench socket thus formed, as illustrated in Fig. 4, so that the driving head may then be turned by power to disconnect the couplings A and B, and when thus disconnected, for example when a new section of pipe is to be added, the drive-pipe sections which extend down into the well will be supported or hung from the driving-head, so that they will not be permitted to drop down into the well.

I am aware that numerous changes may be made in practicing my invention by those who are skilled in the art without departing from the scope thereof as expressed in the claims. I do not wish, therefore, to be

limited to the construction I have herein shown and described, but

What I do claim and desire to secure by Letters Patent of the United States is:—

1. In an apparatus of the class described, the combination of a plate or part having an oil pocket with a return oil channel leading thereto, a rotary head, bearings supporting the rotary-head, and a driving pinion meshing into gear-teeth extending down from the rotary head, the lower edge of the pinion extending down into the oil-pocket, whereby the driving pinion will convey oil from the oil-pocket to said gear-teeth from whence the oil will drip to lubricate the bearings of the rotary head, and will then be returned through the oil-channel to the oil-pocket.

2. In an apparatus of the class described, the combination of a rotary head having a cylindrical body portion with an annular groove therein, a plurality of supporting rollers fitting into said groove and forming the bearings upon which the rotary head turns, and driving gearing for turning the rotary head and for automatically supplying oil to the bearings thereof.

3. In a construction of the class described, the combination of a plate or part having an oil-pocket with an annular return groove leading thereto, a rotary head comprising a cylindrical body portion having an annular groove therein, a plurality of rollers journaled on upright studs and extending into the annular groove to form the bearings on which the rotary head turns, and a driving pinion meshing into teeth extending down from the cover of the rotary head, the lower part of the pinion running in the oil pocket, whereby oil will be conveyed to the gear-teeth from whence it will drip down on to the bearing rolls and be returned through the oil groove.

4. In a drilling machine, the combination of the rotary-head, the driving connections therefor, and two movable sections or cover-plates carried by the rotary-head, said cover plates coöoperating to form a non-circular socket when in closed position to receive and turn a drive-pipe section, and also having abutments coöoperating to form a wrench socket for receiving a drive-pipe coupling, whereby a single set of cover-plates are used for turning the drive-pipe during the drilling, and for coupling and uncoupling additional lengths of drive pipe.

In testimony whereof I have hereunto set my hand, in the presence of two subscribing witnesses.

TURE LARSSON.
